(57) **CLAIM**

The ornamental design for the handheld combustible gas detector, as shown and described.

DESCRIPTION

FIG. 1 is a perspective view of a handheld combustible gas detector;

FIG. 2 is a front view of the handheld combustible gas detector;

FIG. 3 is a rear view of the handheld combustible gas detector;

FIG. 4 is a left side view of the handheld combustible gas detector;

FIG. 5 is a right side view of the handheld combustible gas detector;

FIG. 6 is a top view of the handheld combustible gas detector; and,

FIG. 7 is a bottom view of the handheld combustible gas detector.

The broken lines shown in the drawings illustrate environmental structure and form no part of the claimed design.
